[57] **CLAIM**

The ornamental design for a four point extrusion, as
shown and described.

DESCRIPTION

FIG. 1 is a perspective view of a four point extrusion
showing my new design;

FIG. 2 is a right side elevational view thereof, as
viewed in FIG. 3, the left side elevational view being
substantially identical;

FIG. 3 is a front elevational view thereof, the rear ele-
vational view being substantially identical;

FIG. 4 is a top plan view thereof, the bottom plan view
being substantially identical;

FIG. 5 is a perspective view of a second embodiment of
a four point extrusion showing my new design;

FIG. 6 is a right side elevational view thereof, as
viewed in FIG. 7, the left side elevational view being
substantially identical;

FIG. 7 is a front elevational view thereof, the rear ele-
vational view being substantially identical; and

FIG. 8 is a top plan view thereof, the bottom plan view
being substantially identical.
